STEAM PRODUCING PROCESS

Walter Douglas La Mont, North Colebrook, Conn.,
assignor to W. D. La Mont Inc., Wilmington,
Del., a corporation of Delaware

Original application October 5, 1933, Serial No.
692,236. Divided and this application December
25, 1934, Serial No. 759,131

13 Claims. (Cl. 122—235)

This invention relates to high speed steam and power producing apparatus and high speed methods of operating the same.

This application is a division of my application Serial No. 692,236, filed October 5, 1933.

The method of steam generation in accordance with the present invention makes possible semi-unidirectional flow of the main working fluid in my steam generating elements under conditions of high temperature radiant and convection heat transfer at high rates of heat release.

A main object of my invention is to reduce the size, weight, and cost of high speed steam producing apparatus. I do this by increasing its speed of operation, the detailed means and methods of which are in this case.

By my improved methods of operating steam boilers, I insure their continued performance under long sustained overload conditions through many years of life up to the limit of the maximum heat load conditions for which they are designed, without destroying the boiler, practically regardless of how rapidly combustion temperatures, or load conditions may change, or how fast fluids in all my boiler high speed fluid streams may flow with my improved methods of supercharging and coordinating their various velocities.

It is vital that the main working fluid especially, flow at least semi-unidirectionally at all times, under all steam making loads and speeds, substantially regardless of firebox temperatures or rates of heat release.

In my previous inventions, as disclosed in re-issued U. S. Patent 16,895 and U. S. Patent 1,884,979 and others, using less than sufficient water than would normally be required to fill boiler tubes, I endeavored to secure unidirectional flow of my main working fluid flowing through radiant heat receiving water wall tubes, each tube of considerable length, and of small size, and preferably substantially uniform diameter to insure rapid radiant and convection heat pick up.

Several difficulties were present. When firebox, or so-called combustion chamber pressures, on unburned gases and on burned gases remained down around a few inches of water, and I employed forced circulation with orifices or restrictions, for pressure drop delivery and water distribution purposes at or near the inlet for working fluid entering each long, small diameter boiler tube in my boilers preferably having constant circulation of water through a steam and water separating device I found in the case of

fluid fuel fires, a tendency for these fires to rove back and forth or here and there in the combustion chamber, momentarily intensifying locally certain heat receiving areas in the tubular water wall while these tubes carried rapidly flowing water in their interiors.

With stoker fires it was possible, in each individual installation of water wall in the firebox, when said water wall comprised long tubes of small diameter in accordance with my previous 10 water wall inventions, not using so-called full tubes, to experimentally determine where local hotter areas were, and to provide larger orifices in the water wall tubes passing through these areas and/or accomplish larger pressure drops 15 through the orifices. This preliminary experimental work of determining exactly where local hotter areas were and provide larger orifices in the water wall tubes passing through these areas and/or larger pressure drops through the orifices, 20 was no matter for a novice to undertake, because often in boilers of identical design, intensely hot areas would be found in different places in the walls of the combustion chamber, and further, would wander as fire box temperatures changed, 25 not similarly, for some unaccountable reason, even though all factors may have appeared identical.

With hotter, higher speed, fluid fuel fires, this wandering action becomes a roving action, of 30 great intensity and suddenness, abruptly delivering, or failing to deliver, heats rapidly to certain sections of waterwall tubes at various localized areas, always impossible to determine in advance and constantly changing in position.

These abrupt changes in the heat supplied at localized and constantly varying water wall heat reception areas are due to combustion conditions in the firebox changing constantly.

When rates of heat release or the temperatures in the combustion chamber raised to a high point, steam or water delivery from the outlets of the tubular water wall members develop a rhythm, the wall "pants," (with a noise somewhat like a fatigued animal), the tubes rhythmically belching steam and water, pausing or gulping in their steam and water delivery, then belching more steam and water. The water wall tubes as a whole when acting in the above manner using my pump circulation with orifices at the inlet of the tubes and less than enough water to fill the tubes throughout the length of the tubes, positively deliver water and steam in one path flow to the tube inlets, but this working fluid delivery at the outlets, and throughout the length 55

of the tube is intermittent. It is not continuously uniform nor is it semi-unidirectional nor unidirectional.

There is a distinct difference in the operating 5 characteristics of a so-called full water tube making steam, compared to a tube in which steam is being produced with less than sufficient water to fill the tube; especially when tubes of both types are subjected to exceptionally high 10 rates of heat release, and the condition of semi-unidirectional or unidirectional flow of working fluids is considered.

Other objects of my present invention are to 15 attain a positive and controlled supply of water to each of the steam generating tubes or elements conveying working fluid through the water wall surrounding the combustion zone and through the steam making elements exposed to convection heat; to provide steady and continuous 20 circulation of the water through the water passages or tubes of the water wall or water wall boiler and steam generating elements exposed to convection heat; to provide for the proper and adequate flow of water through the 25 different parts of the steam generating apparatus and in such relation to the steam generated in said parts or to the condition of the steam generated therein that an adequate flow of water may be maintained through each part 30 and in suitable relation in one part relative to the other. It is a still further object of the invention to provide for the positive control of the amount of water delivered to or flowing through the different parts and to control the 35 conditions under which it flows so as to accomplish the proper delivery to and flow through the different parts of the steam generating apparatus to suit conditions of steam generation in said parts.

A still further object of the present invention, 40 is to increase the amount of water circulated and therefore the speed of the circulation of steam and water in the tube with the increase in the rate of heat release, in order to increase the rate of heat transfer from the metal of the tubes to the water and the steam by moving the forming bubbles of steam away from their point of formation faster, thus protecting the water wall tubes especially, and the other tubes of the boiler from the increasing heat to 45 which they are exposed with every increase in the rate of heat release in the combustion chamber.

An important object of this invention is to 50 disclose how so-called full water wall tubes can be operated with positive input of water into each tube in sufficient quantity to protect each tube regardless of how rapid rates of heat release are obtained in the combustion chamber, up to the maximum heat effects for which it is designed to withstand; and to show and describe how semi-unidirectional flow of steam and water within and throughout a portion of the length 55 of the tube can also always be uniformly obtained under any combustion chamber heat releasing condition for which it is designed.

In accordance with my invention, the placing of pressure drop devices beyond the water inlet end of the tubes, or in that part of the tube exposed to radiant and/or convection heat, is 60 a preferred position for these pressure drop devices, or orifices, if orifices are used as pressure drop devices.

Also in accordance with my invention, the pressure drop devices are placed preferably at 65 any point in the tube beyond the point where

steam begins to form, at the designed rate of heat release for the steam generator, thus insuring under the proper load conditions, the passing through the pressure drop device of at least some steam with the water. 5

This immediately gives the advantage of a larger area for steam and water passage through the pressure drop device for a given pressure drop, and a given quantity of water, than would be possible if water alone were passed through 10 the pressure drop device.

This new position of my pressure drop device is also of immediate advantage to reduce the possibility of clogging, whether the steam generator is used, as in my present invention, operating a part of the steam generating tube with a so-called full tube condition, or if the heat release permits, and it is desirable to operate a part of the steam generator under conditions of my previous inventions using less than enough 20 water than is normally required to fill the tube. 15

However, the most desirable position of my pressure drop device is at that position of the length of the tube which at the maximum rates of heat release for which it is designed will 25 insure a sufficient length of the tube to give unidirectional flow of the working fluid so that the steam generator operating as a whole will not have serious steam and water surging conditions caused by that part of the tube in which unidirectional flow is not insured. A steam generating apparatus operating in this way has certain advantages over certain of my previous boiler inventions (using steam generating tubes with less than enough water to fill the tubes 30 in their steam generating portion). Where the rate of heat release is not too great, my new type of steam generator, as outlined herein, can 35 be profitably used.

With the orifices at the inlet end of the tube, 40 as outlined in my reissued U. S. Patent #16,895 and my issued U. S. Patent #1,884,979, and in other patents of mine, practically the whole length of the tube is subject to a surging action as the rate of heat release increases, especially if 45 the tube is operated with the "less than enough water to fill" condition. Such a steam making tube has a non-compact, elastic column of steam and water throughout its length. Sudden high heat effects on a local section of the 50 tube will cause sudden local increase in pressure acting both ways and causing a compression of the column toward the inlet end, as well as toward the outlet end, resulting in a back and forth flow of steam and water in the tube past 55 the orifice which may become violent enough to interfere with the proper operation of the boiler.

By advancing the orifice toward the outlet end of the tube, as in the present invention, the proportion of the length of the tube behind the 60 orifice which has a compact column of steam and water, increases; and the proportion of length past the orifice toward the outlet end, which is subject to the surging action, decreases; reducing the degree of interference to proper steam 65 making operation from back and forth flow or surging flow. The tube under this condition has an assured unidirectional flow for that part of its length between the orifice and the inlet end, while the part of the length from the orifice to 70 the outlet end may have some degree of surging or non-unidirectional flow. This results in the tube as a whole giving what is termed semi-unidirectional flow.

As the rate of heat release increases, the need 75

of advancing the orifice along the tube, toward the outlet end of the tube, likewise increases, until the exit end of the tube is finally reached. This is further discussed in my copending application Serial No. 686,268, filed August 22, 1933.

The selection of the point along the length of the tube where the orifice can best be used is a matter of the general duty for which the apparatus is designed and for which it is to be put in use. The main factors to be considered are,

1. The rate of heat release in the combustion zone.
2. The degree of fluid compactness required to prevent surging in the hydraulic column from behind the orifice to the inlet end of the steam generating tube.

3. The degree of fluid compactness required to prevent surging in the hydraulic column from immediately beyond the orifice to the outlet end of the steam generating tube, in which some surging can be permitted without interfering with the proper steam making operation of the boiler.

4. The amount of water most desirable for circulation.

5. The degree of pressure drop required to insure one path flow and/or semi-unidirectional flow of the working fluid.

6. The size of orifice, or pressure drop device desirable to avoid clogging.

7. Mechanical and boiler cleaning considerations.

8. The question as to whether it is better to operate a portion of the steam generating section with the so-called full tube condition, or with less than sufficient to fill the tubes condition.

In practical application of my previous inventions, using an orifice at or near the entrance to the tube and passing only water through it, I found, especially in waste heat work and with water wall tubes of very short length exposed to moderate rates of heat release; that a very small diameter hole for the orifice in each tube was required to pass the proper amount of water into the tube for the protection of the tube without circulating an unnecessarily large amount of water and to still have a pressure drop of sufficient amount to insure one path flow into the tube.

Without use of distilled water, or in cases where water containing large amounts of carbonates is used; this small orifice at the entrance to each tube, presents a serious problem to prevent clogging which screening of the circulation water line, and of orifices, does not entirely eliminate.

As previously stated, I found that if the orifice is placed at a point in the steam generating element where both steam and water is passed, a much larger hole can be used, or with other forms of resistors or pressure drop devices, much larger areas can be used. This is due to the great increase in the volume of steam compared to water per lb., of either.

If the orifice is placed beyond the point in the tube where steam begins to form there is also a marked increase in the size of the hole which can be used to pass a given amount of water with a given pressure drop.

As the orifice is moved forward in the tube toward the end, the size of the hole used can be increased, reaching a maximum of course, at the outlet end where it will be passing a maximum of steam with the excess water.

I have found that with steam generator units, designed for certain load conditions, using an economizer that gives considerable steam generation at full load, or with an economizer which steams; the art of placing the orifice or pressure drop device at the proper position along the length of the economizer tube to insure semi-unidirectional flow may be used in the same way as previously outlined for waterwall and convection generating tubes. The placing of the orifice or pressure drop device past the point where steam may form is especially advantageous in the economizer to permit the use of larger orifices or pressure drop devices than would be possible if feed water only passed through such devices with sufficient pressure drop to insure one path flow under full load conditions.

A prime object of the present invention is to increase the speed of steam generation and power production, thus making my steam generating apparatus and my steam power plant smaller, lighter weight, and less expensive.

In one of its aspects my invention is a high speed steam generator whose water walls in the radiant heat releasing and receiving area, namely the combustion zone, and whole steam generating tubes exposed to convection heat transfer in the convection heat zone, will not give an undue amount of surging of steam and water travelling back and forth in the tubes but will have positive semi-unidirectional flow of water in each wall tube, at all times, regardless of combustion conditions in the firebox or the size or movement of large steam bubbles shifting from side to side in individual water wall tubes, or group of water wall tubes, up to the maximum rate of combustion at which the steam boiler is designed to operate.

This present invention is particularly concerned with the improvement of high speed steam boilers, and methods of operating said boilers. Where my invention, and/or any of its features, applies to flash boilers, such improvements are well within the scope of my invention as herein described.

While my invention has been described herein as relating to steam generating apparatus which is intended especially for the generation of steam from water, it will be understood that the terms "steam" and "water" as used in the specifications and claims are intended to include as equivalents any liquids which might be handled by the novel process and/or apparatus herein described, resulting in the generation of any vapors which might be handled by or be useful in connection with my process and/or apparatus, and it will also be understood that many of the novel features of this invention are applicable in other fields than that for which the apparatus herein specifically illustrated and described is particularly intended.

Other objects and features will be particularly pointed out and disclosed hereinafter in the illustrations, descriptions, specifications and claims of this present patent application.

In Figure 1 of the drawings is shown a power 65 plant including, as a part thereof, a steam generator adapted to produce steam of high energy content, in accordance with the present invention. The steam generator is designated by 1, 70 having a plurality of steam generator water wall tubes 34 therein receiving water from the water wall inlet header 33, and discharging water and/or steam to the steam generator outlet water wall collecting header 36. These tubes are exposed to a source of radiant heat produced by

a flame fed with fuel from burner 2 in the burner throat 3. The combustion of the fuel oil is assisted by a source of air which may be supplied from the supercharger 5, to which air is admitted through inlet 41, feeding air through the discharge lead 4 to the burner throat. The steam generator tubes are shown fitted with pressure drop devices 35, for controlling the input of water into each tube in sufficient quantity to protect the tube and to control the flow of steam 10 and water in each tube to insure the proper operation thereof, said pressure drop devices being placed in an intermediate portion of the length of each tube, in accordance with the present invention. These devices are shown in 15 greater detail in Figures 3 and 4.

The steam and water collected in header 36 discharges by way of conduits 37 (Figure 2) into water level cylinder 8 for maintaining a water level in the system, furnishing reserve power, 20 and insuring water supply to the circulating pumps. The steam is separated from the water in the cylinder 8, and passes through the main high pressure steam line 9, having main control valve 61 therein for controlling the steam 25 to the main turbine 10. Furthermore, a pipe line 7 extends from the upper end of cylinder 8 to auxiliary steam turbine 6 having control valve 42 therein for controlling the drive of auxiliary turbine 6, which drives the air supercharger 30 fan 5, fuel oil pump 27, boiler feed pump 17 and boiler circulating pump 26.

The main exhaust lead 10^A from the main turbine extends from the latter to the main condenser 11. Pipe 12 represents the inlet for circulating cooling water to the main condenser 11, and pipe 13 is the outlet pipe therefor. Pipe 14 is the condensate water discharge from the main condenser 11 to the main feed tank 15 having feed water inlet 46 and control valve 43 therefor. Vent 47 is associated with the feed water tank, and suction lead 29 extends from the latter to the condensate pump 16 or feed pump 17. 18 is a discharge pipe connecting feed pump 17 with the water level cylinder 8; 19^A is a by-pass line for by-passing feed water around the feed pump 17 through water level regulator valve 19, for controlling the water level in the system; and 20 is a feed stop and check valve on the feed pump discharge lead 18 for stopping and checking the feed of water into the system.

Associated with the cylinder 8 is a safety valve 21 for the boiler at the top of the cylinder, and a blow-off valve 22 at the bottom thereof. The 55 cylinder has a gauge glass 23, and an automatic water level regulator 24^A from which extends a pipe 25 to the control valve 19.

The main steam generator circulating pump is represented at 26. The suction line for pump 26 30 is connected with the water level cylinder 8, through pipe 31, and the discharge pipe 32 of this pump extends therefrom to the inlet header 33. The main circulating pump is fitted with a by-pass 45 therearound, to control the quantity of water which is circulated by means of control valve 44 in this by-pass.

The fuel oil tank is represented at 38 with its suction line 39, vent 50, filling line 48, and control valve therefor, 49, and burner by-pass return oil discharge lead 61^A. Opening into the fuel line into the burner is a pipe having a control valve therein 61^D for introducing starting oil into the burner, and 61^E is a valve for shutting off the oil normally used in the operation of the 70

plant, while using the starting fuel oil. Pipe 28, constituting the exhaust lead from the auxiliary turbine 6, opens into the main turbine exhaust lead 10A.

5 Figures 5 and 6 show schematically arrangements similar to that shown in Figure 1. In Figure 5, the fuel air mixture and burned gases travel substantially parallel to the flow of water in the steam generator tubes fitted with pressure drop devices 35 at intermediate points of the length thereof, in accordance with the present invention. In Figure 6, the gases travel in a counter-current direction to the direction of the flow of water.

15 Figures 7 and 8 show spiral sets of water wall generator tubes fitted with pressure drop devices 35 with each set having an individual circulating pump 26A, 26B, and 26C.

In Figure 9 is shown a complete high speed 20 power plant embodying the highly efficient boiler generating superheated steam. The circulating system for water and fuel resembles that illustrated in Figure 1, and a detailed description of the duplicate parts will not be set forth below.

25 The central combustion chamber 106, as shown, has water wall tubes 34 therein through which water is circulated from inlet header 33 to outlet header 36. The steam and water produced in accordance with the present invention, is discharged into the tube 37 at the end of the boiler opposite the burner, and thence to the water level cylinder 8 where it strikes a baffle plate BP which causes the water in the mixture to be separated and to drop by gravity whereas the steam accumulates at the top of the cylinder for passage therefrom. Tube 51 extends from the upper end of the cylinder 8 at 51A, to deliver saturated steam therefrom to the superheater tubes coiled around the interior of the combustion chamber which are shielded by the water wall tubes 34.

In addition to the steam generating tubes 34 in the combustion chamber, auxiliary steam generating tubes 52 are coiled in annular passage 108, formed on the outside of the combustion chamber 106, and confined by an external wall 202, which forms a tapered passage extending from the inlet thereof at 107, to the outlet thereof, at 109. The combustion gases travel upwardly to the top end of the chamber 106 and then pass through passage 107 downwardly, through the passage 108, giving up the heat contained therein to the steam-generating tubes 52. The tubes 52 may be supplied with circulating water from the main steam generator circulating pump 26 and these tubes discharge the steam and water therein into the water level cylinder at 52A. These tubes 52 in the convection passage may be provided with fins 52B and 52C, extending in parallel to the axis of the tubes, as shown in Figures 14, 15 and 16, for the purpose of more effectively extracting the heat from the combustion gases.

In addition to the steam generating tubes 34 and 52 described above, tubes 55 may be provided for protecting the combustion chamber inlet wall 205, which receive water from the inlet header 33 and discharge water and/or steam to the collecting header 36.

The combustion gases passing downwardly through the convection passage 108, pass through the exits 109A into a series of spirally disposed burnt gas passages 110. These spiral passages terminate near the top of the boiler into a passage 111, which open into a common outlet passage 112, to which is connected the tangential stack outlet passage 113 opening into the atmosphere.

The incoming air used for combustion which is commingled with the fuel supplied by burner 2 in the throat 104, is admitted to the throat through openings 103, after passing in heat-exchanging relationship with the burnt gas passages 110. The air is supplied from the air supercharger 60 (Figure 12), to the pipe 100 opening tangentially into the casing of the boiler 201. This casing forms in conjunction with the walls 203 forming the passages 110, a plurality of spiral 10 air-preheater passages 101, which travel downwardly in Figures 9 and 11 towards the air inlets 103.

In the boilers shown in Figures 9 and 11, an inspection and ignition port 105 is provided covered by detachable closure 212.

The constituent parts of the boiler in accordance with the present invention are preferably constructed of non-corrosive metal alloys. With such a construction it is necessary to properly and thoroughly protect the metal walls from exposure to excessive heat effects from the radiant gases. This is accomplished by placing cooling protective surfaces in front of and in contact with the metal walls.

I claim:

1. In a steam making process, the steps of mixing air and fuel, burning said mixture in a combustion zone, placing liquid working fluid in heat exchanging relation to said burning mixture in said combustion zone thereby producing a mixture of liquid and vaporous working fluid, maintaining a liquid and vapor separation zone, maintaining a liquid level in said separation zone, subjecting said mixture continuously to a drop in pressure at a point in the path of flow thereof, and admitting said working fluid mixture continuously to said separation zone above said liquid level.

2. The method of steam generation which comprises mixing air and fuel, burning said mixture in a combustion zone, continuously circulating a liquid working fluid in heat-exchanging relation to said burning mixture to produce a mixture of liquid and vaporous working fluids, subjecting said mixture continuously at an intermediate point of flow thereof to a drop in pressure, and separating the liquid working fluid from the vaporous working fluid for recirculation in the liquid working fluid circuit.

3. The method of steam generation which comprises mixing air and fuel, burning said mixture in a combustion zone, continuously circulating a liquid working fluid in a plurality of paths in heat-exchanging relation to said burning mixture to produce a plurality of streams containing a mixture of liquid and vaporous working fluids, subjecting each stream of the mixture continuously at an intermediate point of flow thereof to a drop in pressure, and separating the liquid working fluid from the vaporous working fluid for recirculation in the liquid working fluid circuit.

4. The method of steam generation which comprises mixing air and fuel, burning said mixture in a combustion zone, maintaining a convection gas zone in heat exchanging relation to and outside of said combustion zone, continuously emptying burned gases from said combustion zone into said convection zone, placing liquid working fluid in heat exchanging relation to said burning mixture in said combustion zone, placing said liquid working fluid in heat exchanging relation to said burned mixture in said convection gas zone, and subjecting said liquid working fluid to a drop in pressure at a point in the path of flow of said mixture in said combustion zone.

5. In a steam making process, the steps of mixing air and fuel, burning said mixture in a combustion zone, placing liquid working fluid in heat exchanging relation to said burning mixture in said combustion zone thereby producing a mixture of liquid and vaporous working fluid, maintaining a liquid and vapor separation zone, maintaining a liquid level in said separation zone, subjecting said mixture continuously to a drop in pressure at a point in the path of flow thereof, and admitting said working fluid mixture continuously to said separation zone above said liquid level and outside of the range of heat of said burning mixture.
- 10 6. In a vapor generating process the steps of constantly circulating working fluid under pressure, dividing said working fluid in its liquid state into a plurality of separate liquid working fluid streams, placing said separate fluid streams each under pressure, transferring heat to said separate fluid streams, reducing the pressure on the liquid-vapor mixture by a pressure drop at an intermediate point in each of said separate fluid streams, reassembling said separate fluid streams, separating liquid working fluid from its vapor for recirculation in the liquid working fluid streams, and removing said vapor from said circuit.
- 15 7. A process as set forth in claim 6 wherein heat is transferred to said separate fluid streams by the circulation of the heating medium countercurrent to the flow of working fluid in said streams.
- 20 8. A process as set forth in claim 6 wherein heat is transferred from a combustion zone to said separate fluid streams coiled about said combustion zone.
- 25 9. A process as set forth in claim 6 wherein heat is transferred from a combustion zone to said separate fluid streams whirling about said zone countercurrent to burned gases moving through said zone.
- 30 10. A process as set forth in claim 6 wherein said separate fluid streams of liquid-vapor working fluid mixture are reassembled in a liquid and vapor separating zone in which a liquid level is maintained.
- 35 11. A process as set forth in claim 6 wherein heat is transferred to said separate fluid streams by the circulation of the heating medium countercurrent to the flow of working fluid in said streams and wherein said separate fluid streams of liquid-vapor mixture are reassembled in the liquid and vapor separating zone wherein a liquid level is maintained.
- 40 12. A process as set forth in claim 6 wherein heat is transferred from a combustion zone to said separate fluid streams coiled about said combustion zone and wherein said separate fluid streams of liquid-vapor mixture are reassembled in a liquid and vapor separating zone wherein a liquid level is maintained.
- 45 13. A process as set forth in claim 6 wherein heat is transferred from a combustion zone to said separate fluid streams whirling about said zone countercurrent to burnt gases moving through said zone and wherein said separate fluid streams of liquid-vapor mixture are reassembled in a liquid and vapor separating zone wherein a liquid level is maintained.

WALTER DOUGLAS LA MONT. 35
